TAPE EMBOSsing TOOL

William A. Penaluna, Pinole, and Melvin Yee, San Francisco, Calif., assignors to Dymo Industries, Inc., Emeryville, Calif.

Filed Mar. 19, 1970, Ser. No. 21,979

Term of patent 14 years

Int. Cl. D18—99

U.S. Cl. D64—10

FIG. 1 is a perspective view of a tape embossing tool showing our new design;

FIG. 2 is an end elevational view thereof;

FIG. 3 is a side elevational view thereof;

FIG. 4 is an elevational view of the side opposite to that of FIG. 3; and

FIG. 5 is a bottom plan view thereof.

We claim:

The ornamental design for a tape embossing tool, substantially as shown.
